UNITED STATES PATENT OFFICE.

JOHN H. HUNT AND WILLIAM A. CHRYST, OF DAYTON, OHIO, ASSIGNORS TO THE DAYTON ENGINEERING LABORATORIES COMPANY, OF DAYTON, OHIO, A CORPORATION OF OHIO.

IGNITION APPARATUS.

Application filed November 18, 1920. Serial No. 424,837.

To all whom it may concern:

Be it known that we, JOHN H. HUNT and WILLIAM A. CHRYST, citizens of the United States of America, residing at Dayton, county of Montgomery, and State of Ohio, have invented certain new and useful Improvements in Ignition Apparatus, of which the following is a full, clear, and exact description.

10 This invention relates to ignition apparatus for internal-combustion engines. It is one of the objects of the invention to provide improvements in the ignition apparatus described and claimed in the patent to 15 John H. Hunt, No. 1,374,205, dated April 12, 1921. In this application there is described an ignition system in which the passage of current from a battery or other current source to the primary winding of an ignition coil is controlled by the operation of two breaker mechanisms which operate in predetermined sequence, first to connect a portion of the primary turns with the battery and then all of the primary turns with 20 the battery and finally to disconnect the ignition coil from the battery. As described in this application this method of controlling the coil provides for the rapid building up of the coil in order to provide a relatively 25 rapid succession of sparking impulses, while at the same time permitting the timer contacts to be separated while not carrying an excessive amount of current. More particularly it is an object of this invention to improve the make and break devices which control the coil, so that these devices may be 30 operated by a single cam.

It is a further object of the invention to 35 provide improved make and break mechanism which is capable of satisfactory operation at high speed.

A further object of the invention is to provide an ignition unit which shall house the ignition coil, the ignition distributor and the make and break devices, and which may at the same time be conveniently taken apart and reassembled for the purpose of making 40 adjustments and replacements.

Other and further objects of the present 45 invention will be apparent from the following description, reference being had to the accompanying drawings, wherein a preferred embodiment of the present invention is clearly shown.

In the drawings:

Fig. 1 is a side elevation of an ignition unit embodying the invention, partly in section;

Fig. 2 is a sectional view taken on the line 2-2 of Fig. 1, certain parts being omitted for the sake of clearness.

Fig. 3 is a plan view of the timer housing, the distributor head being omitted;

Fig. 4 is a sectional view taken substantially on the line 4-4 of Fig. 3;

Fig. 5 is a sectional view of the break levers shown in Figs. 3 and 4, the section being taken approximately on the line 5-5 of Fig. 4;

Fig. 6 is a sectional view of the timer controlling mechanism taken on the line 6-6 of Fig. 2;

Fig. 7 is a plan view of the timer cam on an enlarged scale;

Fig. 8 is a chart showing the relation of the open and closed periods of the timer contacts;

Fig. 9 is a wiring diagram of the present invention;

Fig. 10 is a sectional view of a portion of the ignition coil, the section being taken on the line 10-10 of Fig. 1; and

Fig. 11 is a bottom view of the coil housing cover looking in the direction of the arrow 11 of Fig. 1.

In the drawings, a housing 20 is divided by a plate 21 into an upper compartment 22, serving as the timer housing, and a lower compartment 23 which encloses the mechanism for controlling the timer cam and distributor. Housing 20 carries a bearing 24 in which is journalled a hollow shaft 25 which terminates at its upper end in a disc 26. Disc 26 carries a plurality of pivotally mounted weight arms 27 normally maintained in their inward position shown in Fig.

6 by means of springs 28, each connected with disc 26 by means of stud 29 and with one of the weights 27 by means of stud 30 (see Fig. 2) passing through a hole in disc 26.

Each weight is provided with a yoke 31 cooperating with an arm 32 projecting radially from a sleeve 33. This sleeve 33 is mounted for rotation about and with a shaft 34 which is journalled within the hollow

shaft 25 and within a bearing 35 carried by plate 21. Connection between the sleeve 33 and the shaft 34 is provided by a pin 36

which passes through a spiral slot 37 in the sleeve 33 and through a straight slot 38 in the shaft 34. This pin also passes diametrically across a collar 40 which slides 5 along the sleeve 33. Collar 40 is provided with a groove 41 into which project studs 42 carried by a yoke 43 mounted upon a shaft 44. A lever 45 is fixed to shaft 44 and by turning this lever 45 the collar 40 may be 10 moved along the sleeve 33 to change the relation between sleeve 33 and shaft 34. Shaft 34 carries a cam 50 and a distributor rotor 140, to be described in detail later. From the foregoing it is apparent that the timing 15 of the ignition may be effected by changing the relation of the shaft 34 to the shaft 25. This is effected manually by turning the lever 45. The automatic control is effected by the movement of the weights 27 away from 20 the shaft 25 as the speed of the shaft increases. This movement of the weights 25 causes the angular relation of the sleeve 33 and the shaft 25 to change. This form of ignition timing control is described and 25 claimed in the copending application of William A. Chryst, Serial No. 254,175 filed September 16, 1918, and further description is considered unnecessary.

The plate 21 carries make and break devices designated generally by numerals 51 30 and 52, Fig. 3. Each of these devices comprises a bracket 53 mounted upon the plate 21 but insulated therefrom by means of a non-conducting member 54. Bracket 53 carries a stationary contact 55 cooperating 35 with a movable contact 56 mounted upon a stud 58 supported by plate 53 but insulated therefrom. A main lever 59 is mounted concentrically with respect to the lever 57 and 40 is provided with a hook 60 curving around the free end of lever 57, and carries a rubbing block 61 which is engaged by the cam 50. Lever 59 carries a pin 62 engaged by a spring 63 secured by a bolt and nut 64, 65 45 to the timer cup 20. This spring normally maintains the lever 59 in the position nearest the cam 50 with the rubbing block 61 in engagement with a stop 66 projecting upwardly from the plate 53. A spring 67 engages 50 the auxiliary lever 57 and a portion of the spring 63 which hooks around the pin 62. This spring 67 serves to maintain the hook 60 normally in engagement with the outer 55 end of the lever 57. The hook 60 therefore limits the moving apart of the levers 57 and 59.

The parts of the make and break device 52 are the same as those of 51. The corresponding parts are designated by the same number but with the affix "a".

In Fig. 7 the relation of the rubbing blocks 61 and 61^a is clearly shown. The cam 50 which revolves in the direction of arrow 50^b is provided with a series of equally 65 spaced lobes 50^a. When either pair of timer

contacts 55, 56, or 55^a, 56^a have just closed, the rubbing blocks corresponding thereto will engage a cam lobe 50^a at point 50^c, and when these contacts have just separated, the rubbing block corresponding thereto will engage a cam lobe 50^a at the point 50^d. If we let the angle A represent the angular distance between cam points in the same phase of the cycle of operation 50^a, and the angle B represent the angular distance between points 50^c and 50^d of any cam lobe, then the angle 70 C will equal A minus angle B. If X equals the angular distance across the face of one of the rubbing blocks, then the period of closure 75 of either pair of timer contacts will equal B plus X, and the period of opening will equal C minus X. Therefore, it will be seen that in a timer device wherein the cam operates with a breaker mechanism to make the ignition circuit, a longer period of closure 80 may be had for the same width of cam lobe, than where the cam operates to break the ignition circuit. These blocks 61 and 61^a need not be of the same thickness, in fact from the operation standpoint, it might 85 be better to make them of different widths. 90

Figs. 3 and 7 show the relation of the cam and make and break devices at a time when the contacts 55 and 56 have just closed. The rubbing block 61 has just been engaged 95 by one of the cam lobes 50^a while the rubbing block 61^a is being maintained by the spring 63^a in its position nearest the cam and in engagement with the stop 66^a. The relation of the open and closed periods of 100 contacts 55, 56 and contacts 55^a, 56^a, as shown in Fig. 8, follows from the relation of the blocks 61 and 61^a to the cam 50. It will be noted that contacts 55, 56 close first, then contacts 55^a, 56^a, close. Then, while 105 contacts 55^a, 56^a, close the contacts 55, 56, open. Then, while contacts 55, 56, are open, the contacts 55^a, 56^a, open.

The timer plate 21 supports resistance 110 units 70 and 70^a which are insulated therefrom. As these units 70 and 70^a are alike the description of unit 70^a will suffice. The corresponding parts of unit 70 are designated without the affix "a". Unit 70^a includes 115 a non-conducting spool 71^a around which is placed a resistance wire 72^a having one end connected with a plate 73^a and the other with a plate 74^a. Plates 73^a and 74^a are held in position upon the spool 71^a by means of 120 non-conducting members 75^a and 76^a which are retained in position by a sleeve 77^a. A screw 78^a passing through sleeve 77^a secures the unit 70^a upon the plate 21. A strap 79^a connects the plate 73^a with the bracket 53^a and a strap 79 connects the plate 73 with the bracket 53. The plates 74 and 74^a are 125 connected with studs 80 and 80^a supported by the timer cup 20 but insulated therefrom.

Distributor head 81 is provided with an 130 annular flange 82 fitting over the timer

housing 20. The head 81 is provided with oppositely projecting ears 83 and 84 provided with holes 85 and 86 respectively through which the studs 80 and 80^a, respectively, project. The head 81 is preferably constructed of bakelite and provided with a rubber track 86 around which the bakelite head has been molded. A plurality of metallic contacts 87 extend from the track surface through the head 81 and terminate in threaded terminals 88 arranged to be engaged by nuts 89 for the purpose of attaching thereto a high tension cable leading to the spark plug of an engine.

15 The head 81 is provided with a coil housing 90 formed concentrically with respect to the track 86. Within this housing 90 an ignition coil 91 is supported. Coil 91 includes a core comprising a center bolt 92 and a bundle of iron rods 93. This core is surrounded by the primary winding 94 and a secondary winding 95. These windings are partially encased within end bells 96 and 97 through which the core members 92 and 93 project.

Referring to Figs. 2 and 10, the end bell 97 is formed with a recess bounded on one side by a straight wall 98, and within this recess are located a plurality of end laminæ 99. Obviously these laminæ 99 cannot turn with respect to the end bell 97. The laminæ 99 are provided with deep notches 100 for reducing loss from eddy currents. The laminæ 99 are provided with centrally located key hole shaped orifices through which passes the center bolt 92 having a portion thereof conforming in cross section to the key hole shaped orifices in the laminæ 99. This portion is designated by numeral 101 and is located just inside the head 102 of the center bolt 92. When in position, the center bolt 92 cannot be turned with relation to the laminæ 99 and hence cannot be turned with relation to the end bell 97.

45 The end bell 97 is provided with lugs 103 and 104 which fit into notches 105 and 106, respectively, provided within the head 81. This interlocking arrangement prevents the end bell 97 from turning with respect to the head 81 when located in position. These lugs 103 and 104 are notched to permit the passage therethrough of conductors 107 and 108, respectively.

Conductor 107 connects the center portion 55 of the primary windings 94 with the coil terminal member 109. Wire 108 connects one end of primary winding 94 with the coil terminal 110. A nut 111 cooperates with a threaded portion of the stud 80 and a spring 113 is interposed between the nut 111 and the terminal 109. By screwing down the nut 111, the head 81 is maintained in position upon the timer housing 20 and an effective connection is made between the terminal 65 109 and the stud 80 and hence between the

terminal 109 and the resistance unit 70 and the make and break device 51.

A nut 112 cooperates with the stud 80^a, and a spring 114 is interposed between the terminal 110 and the nut 112. By screwing 70 down the nut 112 the head 81 is maintained in position upon the timer housing 20 and an effective electrical connection is made between the coil terminal 110 and the stud 80^a, and hence between terminal 110 and 75 resistance element 70^a and make and break device 52.

The end bell 96 supports end laminæ 116 constructed similarly to the laminæ 99. These laminæ 116 abut against the wires 93 80 and are provided with round holes through which the threaded end of the center bolt 92 projects. A cover plate 117 is supported upon the laminæ 116 and a nut 118 cooperates with bolt 92 to secure the coil assembly upon said bolt 92. By screwing down the nut 118 it is apparent that the end bells 96 and 97 and the laminæ 116 will be clamped in position.

The center bolt 92 projects through the 90 upper end of the coil housing 90 and into a recess 120 provided therein. A nut 121 cooperates with bolt 92. By screwing down the nut 121 the coil 91 may be secured within the housing 90 and the ears 103 and 104 of 95 the end bell 97 will be clamped in position within the recesses 105 and 106, respectively. A blind nut 122 provided with a threaded portion 123 is screwed upon the bolt 92 and down against the nut 121 to lock the same in 100 position. After nuts 121 and 122 are in position a quantity of non-conducting material 124 is poured into the recess 120 to make a water-proof joint where the bolt 92 projects through the housing 90. A nut 125 cooperates 105 with the nut 122 to provide a coil terminal.

The other end, from that described, of the primary winding 94 is connected with a clip 130 interposed between the cover plate 117 and the nut 118. To this clip 130 is attached the grounded end 131 of the secondary winding 95. The other end of secondary winding 95 is connected by wire 132, see Fig. 1, with a screw 131^a which passes through a flexible contact 132 and through a coil housing cover 133 and into the end bell 97. Other screws 134 assist in maintaining the coil housing cover 133 in position upon the end bell 97.

A rotor 140 is mounted upon the shaft 120 34 by means of a screw 141 and is driven from cam 50 by means of a locking stud 42 projecting into the rotor 140. A conductor 143 is in engagement with the flexible center contact 132 and with a brush 144 which is yieldingly pressed by spring 145 against the track 86.

The plate 21 supports a condenser bracket 150 on the other side thereof by means of screws 151, and bracket 150 supports con- 130

denser 152 which is grounded upon the bracket at one end and connected at the other end by means of wire 153 with the strap 79^a.

The operation of the invention is as follows:

In the regular order of events, as explained hereinbefore, contacts 55 and 56 close first. When this occurs current flows from a battery 160 which is grounded at 161 and is connected with the terminal 125. The closing of contacts 55, 56 causes current to flow through the following circuit. Battery 160, terminal 125, nut 122, bolt 92, clip 130, a portion of primary winding 94, wire 107, terminal 109, spring 113, nut 111, stud 80, plate 74, resistance wire 72, plate 73, strap 79, contact 55, contact 56, breaker arm 57, spring 63, timer housing 20 to ground. While contacts 55, 56 remain closed, contacts 55^a, 56^a will become closed. When this occurs a part of the current which passed through the upper half of primary winding 94, as viewed in Fig. 2, will now pass through the lower half of primary winding 94 and out through wire 108 to terminal 110. From terminal 110 the circuit will continue through spring 114, nut 112, stud 80^a, plate 74^a, resistance wire 72^a, plate 73^a, strap 79^a, bracket 53^a, contact 55^a, contact 56^a, breaker lever 57^a, spring 63^a and housing 20 to ground. While contacts 55, 56 remain closed, the contacts 55^a, 56^a will open, then all of the current which then flows through the first or upper half of primary winding 94, as viewed in Fig. 2, must flow through this last circuit just described. As described and claimed in the copending application of John H. Hunt referred to, the closing of contacts 55 and 56 causes current to build up relatively rapidly in the ignition coil 91. The opening of contacts 55, 56, while contacts 55^a, 56^a, remain closed, causes the current in the primary windings of the coil to be transformed to a lower value while the energy of the coil remains substantially the same. Then when contacts 55^a, 56^a, open, the amount of current to be interrupted by this opening will not be excessive.

Instead of providing two resistances 70 and 70^a, fair results might be obtained by using one resistance between battery 160 and terminal 125.

While the form of mechanism herein shown and described constitutes a preferred form of embodiment of the invention, it is to be understood that other forms might be adopted, all coming within the scope of the claims which follow.

What we claim is as follows:

1. In an ignition system, the combination with a current source and an ignition coil having a primary winding and a secondary winding; of circuits connecting the battery with different portions of the primary winding; and means for opening and closing said

circuits in recurrent sequence, said circuits having an overlapping closed period, said means including breaker levers each for controlling one of said circuits, and a single cam for operating said breaker levers.

70

2. In an ignition system, the combination with a current source and an ignition coil having a primary winding and a secondary winding; of circuits connecting the battery with different portions of the primary winding; and means for opening and closing said circuits in recurrent sequence, said circuits having an overlapping closed period, said means including breaker levers each for controlling one of said circuits, a single cam for camming said breaker levers into circuit making position, and spring means for restoring said breaker levers into circuit breaking position.

75

3. In an ignition unit, the combination with a timer housing; of a plurality of circuit make and break devices supported within said housing; an ignition coil support and an ignition coil supported thereby; a plurality of coil terminals supported by said coil support and connected with different portions of said coil; means for securing said coil support upon said timer housing, said means connecting certain of said terminals each with one of said make and break devices; and means for actuating said make and break devices.

80

4. In an ignition unit, the combination with a timer housing; of a plurality of pairs of timer contacts supported within said housing; a plurality of resistance elements supported within said housing, each being connected with one contact of each pair of contacts; an ignition coil support and an ignition coil supported thereby; a plurality of coil terminals supported by said coil support, and connected with different portions of said coil; provisions for securing said coil support upon said timer housing and for connecting certain of said terminals each with one of said resistance elements; and means for actuating said pairs of timer contacts.

100

5. In an ignition distributor, the combination with a distributor head having an annular track carrying a circular row of contacts, and a coil housing located concentrically to said row of contacts; of a coil supported by said head within said coil housing; a cover for said coil housing supported by said coil; a center contact supported by said cover and connected to said coil; and a rotor contacting with said track and center contact.

105

6. In an ignition system, the combination of a distributor head having a series of contacts and a recess adapted to receive an ignition coil; a coil supported by said head in said recess; a member closing one end of the recess, said member being supported by

110

115

120

125

130

the coil; a contact supported on the outer surface of said member; and a screw passing through said contact into said member and electrically connecting the coil and contact.

5 7. In an ignition unit, the combination with a timer housing; of a plurality of pairs of timer contacts supported therein; a distributor head covering said timer housing; an ignition coil supported by said head; a plurality of coil terminals supported by said head, and connected with different portions of said coil; provisions for securing said

head upon said housing and for connecting certain of said terminals each with one of said pairs of contacts; a cam for actuating 15 said pairs of contacts; and a distributor rotor.

In testimony whereof we hereto affix our signatures.

JOHN H. HUNT.
WILLIAM A. CHRYST.
